UNITED STATES PATENT OFFICE.

MICHAEL DEERING, OF SYRACUSE, NEW YORK, ASSIGNOR TO CHRISTOPHER C. BRADLEY, OF SAME PLACE.

POWER-HAMMER.

SPECIFICATION forming part of Letters Patent No. 355,512, dated January 4, 1887.

Application filed October 16, 1886. Serial No. 216,417. (No model.)

To all whom it may concern:

Be it known that I, MICHAEL DEERING, of Syracuse, in the county of Onondaga and State of New York, have invented new and useful 5 Improvements in Power-Hammers, of which the following is a specification.

This invention relates to that class of power-hammers in which the hammer-head is attached to a helve by a movable connection; 10 and it has for its object to produce a hammer which is adapted for rapid work, and which will deliver sharp blows in quick succession without heating.

My invention consists of the improvements 15 which will be hereinafter fully set forth, and pointed out in the claims.

In the accompanying drawings, consisting of three sheets, Figure 1 is a side elevation of my improved hammer. Fig. 2 is a sectional 20 elevation of one of the rubber springs on an enlarged scale. Fig. 3 is a side elevation of the head portion of the hammer on an enlarged scale. Fig. 4 is a front elevation thereof. Fig. 5 is a top plan view thereof. Fig. 6 is a sectional elevation of one of the spring-levers and connecting parts. Fig. 7 is a sectional elevation of the head portion of the hammer, showing a modified arrangement of the sprung-levers. Fig. 8 is a top plan view of said levers. 25 Fig. 9 is a side elevation of the hammer, showing another modified arrangement of the spring-levers. Fig. 10 is a sectional elevation, on an enlarged scale, of the head portion of the hammer shown in Fig. 9. Fig. 11 is a front elevation thereof. Fig. 12 is a top plan 30 view thereof.

Like letters of reference refer to like parts in the several figures.

A represents the main frame of the hammer, 40 and a the anvil thereof.

B represents the hammer-head sliding between vertical ways b, formed on the main frame A.

C represents the helve, which is pivoted to 45 the main frame at c, and which is operated from the driving-shaft d by a connecting-rod, D, in any suitable manner.

E E' represent two levers, pivoted to the front portion of the helve by horizontal bolts 50 e e', the levers being arranged between the two

bars of which the front portion of the helve is composed.

F represents a strap or flexible connection, by which the lower ends of the levers E E' are connected with the upper end of the hammer-head B, which latter is provided with an opening, f, through which the strap F passes. 55

The levers E E' are arranged, respectively, in front and in rear of the hammer-head B. The lower ends of the levers E E' are bifurcated 60 and provided with collars or sleeves g, around which the strap F passes, and which are mounted on horizontal bolts g', attached to said levers.

In the construction represented in Figs. 1, 3, 4, 5, and 6 the upper arms, h h', of the levers E E' are arranged horizontally and bear against the lower sides of two springs, I I'. The arm h of the lever E extends rearwardly from the pivot e, and the arm h' extends forwardly from the pivot e'. The springs I I' are arranged one behind the other above the helve, and are supported by bows or bridge-pieces H H', which are secured with their lower ends to the helve, and carry at their upper ends set-screws j j', 75 by which the springs I I' are adjusted. Each of the springs I I' is provided at its upper end with a metallic cup, J, against which the set-screw bears, and at its middle with a flanged metallic diaphragm, J', whereby the two portions of each spring are held against lateral displacement. Each spring is preferably provided with a central aperture, in a well-known manner, to facilitate the operation of vulcanizing the rubber. By tightening the set-screws 80 j j' the levers E E' are swung on their pivots, so as to tighten the strap F. The springs I I' cushion the blow and enable the hammer to be operated at a high speed, delivering sharp 85 blows in quick succession without heating, even when the material between the hammer and anvil is very thin—as, for instance, in plating butcher and case knives. The cushioning afforded by the springs applied to the pivoted levers at the head of the helve permits 90 the omission of the cushioned yoke usually employed in helve-hammers, thereby greatly simplifying the construction of the hammer. 95

In the construction represented in Figs. 7 and 8 the upper arms, k k', of the levers E E' 100

extend past each other and bear against opposite sides of a single spring, K, which is interposed between the upwardly-projecting ends of the upper arms, k k'. The latter are 5 provided with set-screws ll', which bear against opposite ends of the spring.

In the construction represented in Figs. 9, 10, 11, and 12 the upper arms, m m', of the levers E E' project upwardly from their pivots, and two springs, M M', are arranged against the outer sides of the arms m m'. These springs are connected by a horizontal screw-rod, n, which passes through the arms m m' and the springs M M', and is provided on the outer 15 sides of said springs with screw-nuts o o', whereby the levers and springs are adjusted.

I claim as my invention—

1. The combination, with the helve and the hammer-head, of levers pivoted to the helve, 20 and a flexible connection whereby said levers are connected with the hammer-head, substantially as set forth.

2. The combination, with the helve and the hammer-head, of levers pivoted to the helve, 25 a flexible connection whereby said levers are connected with the hammer-head, and an elastic cushion applied to said levers, substantially as set forth.

3. The combination, with the helve and the hammer-head, of levers pivoted to the helve, 30 a flexible connection whereby said levers are connected with the hammer-head, and adjusting devices whereby the levers are adjusted, substantially as set forth.

4. The combination, with the helve and the hammer-head, of levers pivoted to the helve, 35 a flexible connection whereby said levers are connected with the hammer-head, an elastic cushion applied to said levers, and adjusting devices whereby the levers and cushion are 40 adjusted, substantially as set forth.

5. The combination, with the helve and the hammer-head, of levers E E', pivoted to the helve, a flexible strap, F, connecting the lower ends with the hammer-head, springs I I', resting on the upper ends of said levers, and bridge-pieces H H', secured to the helve and supporting the upper ends of said springs, substantially as set forth.

Witness my hand this 29th day of September, 50
1886.

MICHAEL DEERING.
